UNITED STATES PATENT OFFICE

PETER L. KNIGHT, OF WILMINGTON, NORTH CAROLINA

PICTURE HANGER

Application filed February 4, 1930. Serial No. 425,870.

This invention relates to picture hangers, and it is an object of the invention to provide a device of this kind which, when in applied or working position, is concealed by the picture with which it is employed.

It is also an object of the invention to provide a device of this kind whereby the picture is supported in a manner to eliminate wobbling or other derangement of the picture and wherein the mounted picture is effectively braced against displacement from the action of draft or wind.

An additional object of the invention is to provide a device of this kind wherein the major portion of the weight of the picture is imposed from above upon the device, thus relieving the lower portion of the picture frame from the load which would otherwise be imposed thereon.

The invention consists in the details of construction and in the combination and arrangement of the several parts of my improved picture hanger whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in rear elevation of a hanger constructed in accordance with an embodiment of my invention having a picture operatively engaged therewith;

Figure 2 is a view in front elevation of the hanger as illustrated in Figure 1 with the picture omitted;

Figure 3 is a view in side elevation of the hanger as illustrated in Figure 1 with the associated picture being diagrammatically indicated by broken lines;

Figure 4 is a sectional view taken substantially on the line 4—4 of Figure 2 looking in the direction of the arrows;

Figure 5 is a sectional view taken substantially on the line 5—5 of Figure 2 looking in the direction of the arrows;

Figure 6 is a fragmentary elevational view illustrating another embodiment of my invention;

Figure 7 is a sectional view taken substantially on the line 7—7 of Figure 6 looking in the direction of the arrows;

Figure 8 is a view partly in elevation and partly in section of another embodiment of my invention;

Figure 9 is a fragmentary view in side elevation of the structure illustrated in Figure 8;

Figure 10 is a fragmentary view in top plan of the structure illustrated in Figure 8;

Figure 11 is a detailed sectional view taken substantially on the line 11—11 of Figure 10;

Figure 12 is a view in front elevation illustrating a hanger constructed in accordance with a still further embodiment of my invention;

Figure 13 is a sectional view taken substantially on the line 13—13 of Figure 12;

Figure 14 is a fragmentary elevational view illustrating a hanger constructed in accordance with an additional embodiment of my invention;

Figure 15 is a sectional view taken substantially on the line 15—15 of Figure 14;

Figure 16 is a fragmentary elevational view of another embodiment of my invention;

Figure 17 is a sectional view taken substantially on the line 17—17 of Figure 16.

In the embodiment of my invention as particularly illustrated in Figures 1, 2 and 3, the hanger comprises an elongated plate 1 of desired dimensions and material and which is provided at substantially its transverse center with a plurality of longitudinally aligned

openings 2 affording means whereby any suitable type of headed members 3 may be employed for securely anchoring the device in position upon a wall or other desired support.

- 5 At substantially its transverse center the upper part of the plate 1 is provided with an upstanding and upwardly facing hook member 4 and at points below the hook member 4 and adjacent to its opposite margins, the 10 plate 1 is provided with the eye members or loops 5. The members or loops 5 are preferably coplanar in a direction transversely of the plate 1 and are positioned for relatively close proximity to the hook member 4.
- 15 The lower end portion of the plate 1 is provided with a forwardly or outwardly disposed ledge or foot 6 directed transversely of the plate 1 and substantially perpendicular thereto. The outer corner portions of the 20 ledge or foot 6 are provided with the upstanding pointed or penetrating members 7. The plate 1 is adapted to be suitably anchored in position upon a wall or other support and when so applied is in position to have operatively engaged therewith the picture to be hung. In referring to a picture it is to be understood that I have in mind the picture itself together with a frame and other associated parts.

- 25 30 In applying the picture P, as indicated by broken lines in Figure 3, the lower edge thereof is supported directly by the ledge or foot 6 and with the lower marginal face of the picture preferably in direct engagement from above with the members 7, said members impinging or penetrating the picture and thus affording an effective means to hold the picture against slippage with respect to the plate 1 and otherwise serve to maintain the picture 35 in desired position.

40 The rear of the picture has secured thereto in a conventional manner, as at 8, the extremities of a picture wire 9 or the like which has its intermediate portion engaged over the 45 hook member 4 or through the eye members 5 or, if desired, in operative engagement with both. By this means the hanger is substantially concealed behind the applied picture, yet at the same time the picture P is supported in a manner to hold the same against wobbling and to resist displacement by the action 50 of wind or draft or other causes, such as building vibration.

55 In the embodiment of my invention as illustrated in Figures 6 and 7, the lower end portion of the plate 1' is provided with the outwardly disposed elongated arms 10 provided at their outer or free extremities with the upstanding pointed or penetrating members 7'. The arms 10 serve as a shelf or foot and in this embodiment of my invention the hanger is otherwise constructed as hereinbefore set forth with respect to Figures 1 to 5 inclusive and the picture is engaged therewith in the same manner.

60 In Figures 8 to 11 inclusive I set forth an embodiment of my invention which is especially adapted for store or gallery display and wherein the hanger is adapted to be operatively engaged with a supporting rod 11. The rod 11 is provided at one extremity with a depending arm or pintle 12 freely disposed through a supporting member 14 whereby the rod 11 may be readily swung or adjusted as may be preferred. In connection with a 75 single hanger I find it of advantage to employ a plurality of rods 11, thus assuring the picture associated therewith being supported with a maximum of efficiency.

70 80 In this embodiment of my invention the hanger comprises a plate 1a provided with a hook member 4a and the eye members 5a as hereinbefore set forth with respect to the first embodiment of my invention. The plate 1a also carries the outstanding foot or ledge 6a. The rear face of the plate 1a has welded, soldered or otherwise secured thereto the longitudinally aligned blocks 15 which are adapted to snugly and slidably engage the rods 11 and locked to the rods 11 in desired 85 selective position through the instrumentality of the binding screws 16.

90 95 In this embodiment of my invention, the ledge or foot 6a has associated therewith a supplemental ledge or foot 17 adapted to be adjusted toward or from the plate 1a as desired and which supplemental foot or ledge 17 is locked in desired adjustment through the medium of one or more clamping elements, generally indicated at 18. The supplemental foot or ledge 17 carries the upstanding members 7a which, in the present embodiment of my invention, may be extended in advance of the lower portion of an associated picture to facilitate the maintenance 100 of the picture in desired applied position with respect to the hanger.

105 110 The embodiment of my invention as illustrated in Figures 12 and 13 is substantially the same as that shown in Figures 1 to 5 inclusive except that the main or body plate comprises two lapping sections 1'', said sections at substantially their transverse centers being provided with the longitudinally spaced openings 19 and 20 with which are 115 selectively engaged the holding screws 21. By this means the hanger may be readily and conveniently adjusted as to length in order to permit the hanger to be employed to advantage and effect in connection with pictures of varying sizes.

120 125 The invention as illustrated in Figure 14 is also substantially the same as hereinbefore described except that the eye members 5' are provided by pressing out portions of the plate 1b and providing said outwardly pressed or disposed portions with suitable openings. In this arrangement it is to be noted that the eye members 5' are contained within the field of the plate 1b. It is to be 130

herein stated that these same forms of eye members are equally adaptable to the other embodiments of my invention hereinbefore set forth.

5 In the embodiment of my invention as illustrated in Figures 16 and 17 the lower portion of the plate 1c is provided with the slots or recesses 22 each of which being adapted to receive an extended part or member 23 carried by the lower portion of the picture, or more particularly the picture frame, whereby such picture is effectively supported by the hanger. It is to be understood that the slots or recesses 22 are of such 10 a character as to permit the plate 1c to support the applied picture from below.

From the foregoing description it is thought to be obvious that a picture hanger constructed in accordance with my invention 20 is particularly well adapted for use by reason of the convenience and facility with which it may be assembled and operated, and it will also be obvious that my invention is susceptible of some change and modification 25 without departing from the principles and spirit thereof and for this reason I do not wish to be understood as limiting myself to the precise arrangement and formation of the several parts herein shown in carrying 30 out my invention in practice except as hereinafter claimed.

I claim:—

1. A picture hanger comprising a plate-like member provided with a ledge to engage 35 a marginal portion of a picture frame or the like, and cord engaging means carried by the plate-like member on the opposite marginal edge portions thereof above the ledge, the outer portions of the ledge being provided 40 with upstanding members, said cord engaging means being mounted on the edges of the plate in outstanding relation thereto.

2. A picture hanger comprising a plate-like member provided with a ledge to engage 45 a marginal portion of a picture frame or the like, and cord engaging means carried by the plate-like member on the opposite marginal edge portions thereof above the ledge, the outer portions of the ledge being provided 50 with upstanding pointed members, said cord engaging means being mounted on the edges of the plate in outstanding relation thereto.

55 3. A picture hanger comprising a plate member provided with a ledge for engagement with a picture frame or the like from below, and means carried by the plate member above the ledge for coaction with the picture frame or the like to hold said frame or the like in desired position with respect to the ledge, said means including eye portions carried by the plate in outstanding relation on the marginal edges thereof through which a picture cord is adapted to be directed.

60 65 4. A picture hanger comprising a plate

member provided with a ledge for engagement with a picture frame or the like from below, and means carried by the plate member above the ledge for coaction with the picture frame or the like to hold said frame or the like in desired position with respect to the ledge, said means comprising a cord engaging hook member carried by the plate in outstanding relation to the plate and intermediate the marginal edges thereof.

In testimony whereof I hereunto affix my signature.

PETER L. KNIGHT.
